UNITED STATES PATENT OFFICE.

HENRY J. P. ROTTGER, OF NEW YORK, N. Y.

SHOE HEEL.

Application filed November 23, 1922. Serial No. 602,674.

To all whom it may concern:

Be it known that I, HENRY J. P. ROTTGER, a citizen of the United States, residing at Maspeth, in the borough of Queens, city 5 and State of New York, have invented an Improvement in Shoe Heels, of which the following is a specification.

This invention relates to a shoe heel and more particularly to that type of heels for 10 boots and shoes in which there is provided a revoluble tread and devices for turning the revoluble tread a partial revolution each time the heel is raised from contact with the walking surface. The object of the invention is the provision of a heel of this 15 type which is of comparatively inexpensive construction and which is preferably operated through gears and associated mechanism so as to cause the action thereof to 20 be absolutely positive, and the shoe heel made in accordance with my invention will be hereinafter more particularly described.

In the drawing:

Fig. 1 is a side elevation and partial section showing the application of my improved heel in use in a slipper.

Fig. 2 is an enlarged central cross section showing the tread member in the raised position.

Fig. 3 is a similar view showing the tread member in the lowered position.

Fig. 4 is a section on line 4—4, Fig. 3, and

Fig. 5 is a sectional elevation illustrating the construction of the drum, gear, collar and shaft employed in the heel.

By reference to the drawing it will be seen that in carrying out the invention I employ a heel, the body portion of which is indicated at 10; and which may be made 40 of any suitable material and provided with a hole or opening 11. As will be understood the body of the heel may be attached to a slipper 12 or a boot or shoe in any suitable manner.

At the lower or outer end of the heel I employ a plate 13 which may be connected to this end of the body of the heel in any desired manner. At the opposite end of the heel, that is at the upper or inner end there- 50 of or adjacent the same there is a cross plate or bar 14. This is set in oppositely disposed recesses provided therefor, and one end 15 of the cross plate is secured to the

heel by a screw 16 and the opposite end 17 of the cross plate is similarly secured 55 in the heel by a screw 18.

Mounted in the plate 13 there is a drum 19. This is journaled in an opening 20 in the plate 13 which provides a bearing therefor.

At the inner end of the drum 19 there is 60 a flange 21 normally adapted to bear against the inner surface of the plate, it being understood that the drum 19 is revoluble in the bearing and also shiftable therein longitudinally of the heel. I also employ a shaft 65

22. At one end this is provided with a circularly flanged head 23 adapted to be received in a recess 24 provided therefor in the inner end of the drum 19. Mounted 70 on the shaft 22 there is a sleeve 25. This sleeve 25 also extends into an opening 26 provided therefor in the inner end of the drum 19 and is suitably connected to the drum 19 in any manner to permit the drum and sleeve to also turn on the shaft 22 and 75

the head 23 thereof. At the outer end of the sleeve 25 there is a bevel gear 27. This, as will be understood, may be made an integral part of the sleeve or connected there- 80

to in any suitable manner. The opposite or inner end of the shaft 22 is flattened as indicated at 28 and passes through a slot provided therefor and acting as a bearing 85

in the cross plate or bar 14. These parts are normally maintained in the position in- 90

dicated in Fig. 3 by a spring 30, secured at one end between the head of the screw 16 and the upper face of the cross plate or bar 14 and bearing at its opposite end 95

against the flattened end of the shaft 22. By this structure, as will be understood, the drum 19 and its flange 21 are revoluble in the bearing in the plate 13 and are also 100

adapted to turn on the outer end of the shaft 22, together with the sleeve 25 and its bevel gear 27, while these parts together with the shaft 22 are shiftable longitudinally of the heel and the shaft is prevented from turning because of its flattened end passing through 105

and being movable in the slot 29 in the cross plate or bar 14.

Suitably fixed in and extending from the shaft 22 there is a stub shaft 31. Mounted 110 on this stub shaft is a disk 32. Connected to the disk 32 at one side thereof is a bevel gear 33 adapted to mesh with the bevel gear

27, while at the opposite side of the disk 32 there is a ratchet 34. Associated with the ratchet there is a pawl 35 which is pivotally connected at one end as indicated at 5 36 to the side of the cross plate or bar 14, while the free or latch end of the pawl is adapted to engage the teeth of the ratchet. The pawl is normally maintained in position with the latch end thereof in engagement with the teeth of the ratchet by means of a spring 37 or otherwise.

I also employ a tread member which, as indicated, may include a plate 38 which is secured to the under or outer surface of the 15 drum 19 by means of screws 39 or otherwise and to which plate 38 a suitable tread member 40 is attached in any desired manner, it being understood that this tread member may be made of leather, or rubber or other 20 material of which heel treads are commonly constructed. It will be noted that the tread member 40 is centrally recessed as indicated at 41 not only for the purpose of making it possible to readily attach the plate 38 to the 25 drum 19, but it provides an annular or tread surface for the heel so as to make it impossible for the tread member to wear into a conical formation, it being obvious that as the wear is on the outer edge of the tread 30 member in the revolution of the tread member it would wear into the form of a cone if it were made to extend entirely across the bottom of the heel, whereas because of the central recess therein the wear on the 35 heel can only create an inclined surface extending from the outer edge to the recessed portion of the tread member.

In the use and operation of the devices comprising the heel as hereinbefore described, the parts are normally maintained in the position shown in Fig. 3 and when the heel is brought into contact with the walking surface the tread member and the parts associated therewith are shifted longitudinally of the heel to the position shown 45 in Fig. 2. In this shifting of the parts the drum with the shaft and the gears carried thereby are moved inwardly against the action of the spring 30. In so doing, as will 50 be obvious, the latch or dog end of the pawl rides over one or more of the teeth of the ratchet 34. When the heel is raised the action of the spring against the shaft returns the same and the drum with the revoluble tread member to the position shown 55 in Fig. 3. In so doing the ratchet 34 in moving outwardly will be turned a partial revolution transmitting a corresponding movement to the bevel gear 33 which is 60 transmitted to the bevel gear 27 thereby turning the sleeve 25 and the drum 19 a partial revolution which is also transmitted to the tread member so that each time the heel is raised and returned to the tread surface the tread member is revolved a partial

revolution to bring a new section thereof at the rear of the heel where in most cases it is first brought into contact with the tread surface. This, as will be apparent, causes the tread surface of the heel to wear 70 evenly.

I claim as my invention:

1. In a heel for boots and shoes, a heel body having an opening therein, a plate at the outer end of the heel body, a revoluble 75 tread, a device passing through and journaled in the said plate and to which the said revoluble tread is attached, a shaft upon which the said device is revolubly mounted, the said shaft, together with the 80 device and tread attached thereto, being movable longitudinally of the heel, and means for imparting a partial revolution to the said device and revoluble tread each time the heel is lifted from a walking 85 surface.

2. In a heel for boots and shoes, a heel body having an opening therein, a plate secured to the outer end of the heel, a revoluble member mounted in the said 90 plate, a tread member secured to the said, revoluble member, means for normally maintaining the said tread member in a position spaced from the said plate, bevel gears, and devices for actuating the said 95 gears to turn the tread member a partial revolution each time the heel is raised from a walking surface.

3. In a heel for boots and shoes, a heel body having an opening therein, a plate 100 attached to the outer end of the heel body, a drum passing through and journaled in the said plate, a tread member attached to the drum, a shaft upon which the said drum is revolubly mounted, the said shaft, drum 105 and tread being movable longitudinally of the heel, means for normally maintaining the drum and tread member in a position in which the tread member is spaced from the plate, and devices for imparting a partial revolution to the said drum and tread member each time the heel is lifted from a walking surface.

4. In a heel for boots and shoes, a heel body having an opening therein, a plate attached to the outer end of the heel, a drum mounted in the plate to be revoluble therein and also shiftable longitudinally of the heel, a tread member secured to the said drum in a position normally spaced from 115 the said plate, a bevel gear connected to the said drum, a support, a bevel gear mounted in the said support and meshing with the aforesaid gear, means for normally maintaining the drum and tread member in a position spaced from the plate, and devices for actuating the said gears to impart a partial revolution to the said tread member 120 each time the heel is raised from a walking 125 surface.

5. In a heel for boots and shoes, a heel body having an opening therein, a plate attached to the outer end of the heel, a drum mounted in the plate to be revoluble therein and also shiftable longitudinally of the heel, a tread member secured to the said drum in a position normally spaced from the said plate, a bevel gear connected to the said drum, a shaft upon which the drum and gear are revoluble, a stub shaft secured in the aforesaid shaft, a bevel gear mounted on the stub shaft and meshing with the aforesaid bevel gear, a cross bar connected to the said heel body and extending across the opening in the same, the said shaft having a flattened end portion passing through a part of the cross bar to prevent the shaft from turning, a spring connected in the said cross bar and bearing against the end of the said shaft to normally maintain the shaft, the gears and the drum in a position in which the tread member is spaced from the plate, and devices for turning the said gears a partial revolution to impart a similar movement to the said tread member each time the heel is raised from a walking surface. 70
- 10 6. In a heel for boots and shoes, a heel body having an opening therein, a plate attached to the outer end of the heel, a drum mounted in the plate to be revoluble therein and also shiftable longitudinally of the heel, 75 a tread member secured to the said drum in a position normally spaced from the said plate, a bevel gear connected to the said drum, a shaft upon which the drum and gear are revoluble, a stub shaft secured in the aforesaid shaft, a bevel gear mounted on the stub shaft and meshing with the aforesaid bevel gear, a cross bar connected to the said heel body and extending across the opening in the same, the said shaft having a flattened end portion passing through 80 a part of the cross bar to prevent the shaft from turning, a spring connected in the said cross bar and bearing against the end of the said shaft to normally maintain the shaft, the gears and the drum in a position 85 in which the tread member is spaced from the plate, a ratchet connected to the last aforesaid bevel gear, and a dog mounted on the said cross bar and adapted to engage the teeth of the said ratchet whereby the ratchet is turned to move the bevel gears and thus impart a partial revolution to the revoluble member each time the heel is raised from a walking surface. 90
- 15 7. In a heel for boots and shoes, a heel body having an opening therein, a plate attached to the outer end of the heel, a drum mounted in the plate to be revoluble therein and also shiftable longitudinally of the heel, 95 a tread member secured to the said drum in a position normally spaced from the said plate, a bevel gear connected to the said drum, a shaft upon which the drum

Signed by me this 6th day of November, 100
